UNITED STATES PATENT OFFICE.

KARL HAMPEL, OF DETROIT, MICHIGAN, ASSIGNOR TO MICHAEL ZAKMAN, OF CHICAGO, ILLINOIS.

GAME.

Application filed March 21, 1921. Serial No. 453,912.

To all whom it may concern:

Be it known that I, KARL HAMPEL, a citizen of Jugo-Slavia, residing at Detroit, in the county of Wayne and State of Michigan, have invented certain new and useful Improvements in Games, of which the following is a specification, reference being had therein to the accompanying drawings.

This invention relates to a game apparatus in which a dart is thrown against a target, the dart being so constructed that when its needle point has become embedded in the surface of the target and an attempt is made to withdraw the dart, the needle point will remain sticking in the material of the target and will be withdrawn from the dart so that the same may be used successively with a plurality of points and the total score obtained by a number of throws may be readily determined at the conclusion of the series by assigning to each of the needles remaining in the target the values as determined by its location on the target.

The object of my present invention is to provide a simple form of socket at the tip of the dart which will hold the needle firmly enough to prevent it dropping out with ordinary handling but in which the friction between the needle and the socket will be less than the friction between the needle and the target so that when the dart is withdrawn the needle will cling to the target instead of to the dart.

A further object of my invention is to provide a simple construction of the vanes for guiding the flight of the dart through the air.

Another object of my invention is to provide a simple means for preventing the splitting of the point end of the dart.

With the above primary and other incidental objects in view, as will more fully appear in the specification, the invention consists of the features of construction, the parts and combinations thereof, and the mode of operation, or their equivalents as hereinafter described and set forth in the claims.

In the drawing,

Figure 1 is a perspective view of a preferred form of dart;

Fig. 2 is an end elevation of the rear end of the dart;

Fig. 3 is a longitudinal section, partly in elevation of the front end of the dart; and

Fig. 4 is an elevation of the target.

The dart consists preferably of a cylindrical wooden shaft 1, having a kerf at its rear end to receive the vanes 2, which may be of celluloid or other suitable light stiff or resilient material. The vanes may be secured in the kerf by any suitable fastening means, as for example a staple 3. The other or front end of the dart is provided with a diametral kerf or slit 4 and a bore 5 extending a less distance than the kerf into the dart. Placed at the bottom of the bore is a cylindrical block of a resistant material, such as a short length of wire, which forms an abutment against which the needle 7 engages when it is placed in the outer end of the bore. A sleeve 8 preferably of metal surrounds the body of the dart opposite the end of the kerf 4 and not only serves to prevent splitting of the dart but also adds a certain weight near the point of the dart. It is preferably split to permit limited outward movement of the split ends of the dart.

The bore 5 is preferably of such size that the ordinary metallic phonograph needles may be used for the points 7 and for this purpose used needles will be entirely satisfactory since the points of the used needles will not be worn enough to make them too dull to stick into a target of the kind intended to be used for the game.

The bore will of course be slightly smaller in diameter than that of the needle so that the walls of the bore will be spread when the needle is inserted, the kerf permitting such outward movement.

The block 6 engages the bottom of the bore 5 with a flat end. It thus serves as an abutment to prevent the needle 7 from being driven into the bore 5 by the force of its contact with the target far enough to become wedged so tightly as not to be readily withdrawn from the dart. The block 6 also limits the extent to which the needle can be inserted into the shaft 1 so as to assure that the needles will project the proper distance beyond the end of the wood. It also aids in

5 preventing splitting of the wood or injury to the bottom of the bore 5, which might occur if such block were absent and the needles were driven against the wood at the bottom of the bore with considerable force such as might be exerted by contact of the point of the needle with some harder surface than that of the target.

10 The target 9 consists preferably of a sheet of paper secured to the surface of a backing material soft enough to be readily penetrated by the sharp needle points yet having sufficient firmness to retain the points with sufficient friction so that the needles will remain 15 in the target when the dart is withdrawn.

This material must also be of sufficient strength to prevent penetration by the wooden end of the dart.

20 Suitable materials for this purpose are cork, corrugated paste-board, certain varieties of wall board, or a soft wood.

25 Upon the surface of the target will be printed a design on which will preferably be indicated the amount to be scored by the player whenever the needle point strikes within certain boundaries. As shown in the drawing, the highest score will be made when the needle point strikes within the central circle, this counting twenty-five. If 30 the needle strikes outside this central area but within the next ring, a score of fifteen will be counted, and so on as indicated for each of the areas of the target.

35 Each player may be allowed a certain number of trials at the target and the dart may be thrown in any way desired. The manner of throwing the dart and the distance at which the player shall sit or stand while throwing the dart may be agreed upon 40 to suit the players.

45 After the dart has been thrown and the point has become embedded in the material of the target, a pull upon the dart to release it will cause the dart to be withdrawn from the point since the friction between the point and the dart will be made less than the friction existing between the point and the material of the target. After a player has completed his turn, the needles may be withdrawn by the fingers and the score computed 50 according to the areas within which the needle points lie. If needles having different colors or other distinguishing characteristics are used, each of the players may continue 55 using the target without withdrawing the points, and the total score for each of the players may be determined at the conclusion of the game by computing the total score attained by all of the points having the same 60 color or other characteristic.

65 From the above description, it will be apparent that there is thus provided a device of the character described possessing the particular features of advantage before enumerated as desirable, but which obviously

is susceptible of modification in its form, proportions, details of construction, and arrangement of parts without departure from the principle involved or sacrificing any of its advantages.

70

While in order to comply with the statute the invention has been described in language more or less specific as to structural features, it is to be understood that the invention is not limited to the specific details shown but 75 that the means and construction herein disclosed comprise but one of several modes of putting the invention into effect, and the invention is therefore claimed in any of the forms or modifications within the limitations 80 and valid scope of the appended claims.

85

I claim:—

1. The combination with a dart having a point held therein by friction, of a target 90 constructed of a material adapted to be penetrated by the point of the dart, the friction existing between the dart and the point being less than the friction between the point and the target, when the point is embedded therein, whereby relative movement between the body of the dart and the target will cause the withdrawal of the point from the dart.

95 2. A game apparatus comprising a dart having a needle point held in one end thereof by friction and a target constructed of a material adapted to be penetrated by the needle point and adapted to hold the point when penetrated thereby with a greater friction than the friction between the dart 100 and the needle point whereby the needle point will remain in the target when the dart is withdrawn, the apparatus having indicating characteristics whereby to permit scoring.

105 3. A dart having at its forward end an axial bore to receive a separable point, said dart having a diametral slit extending inward from the end of the dart to permit yielding of the walls of the bore.

110 4. A dart having at one end an axial bore to receive a frictionally held point and a block of resistant material of less length than the bore and positioned at the inner end thereof to limit the inward movement of 115 the point.

120 5. A dart having at one end thereof a longitudinal bore and a separable frictionally held point for the dart adapted to be inserted into the bore, the length of the point being such that, when its inner end has been inserted to a point at which further inward movement is prevented, a penetrating end projects beyond the end of the dart.

125 6. A structure as in claim 5, in which a resistant body is positioned at the inner end of the bore to limit the inward movement of the dart.

130 7. A dart having at one end a longitudinal bore and a separable frictionally held

point for the dart adapted to be partially inserted into the bore, the inner end of the point having a substantially blunt end and the outer end being provided with a penetrating point.

8. A game apparatus comprising a target and a dart, the dart being provided at its forward end with a longitudinal bore adapted to receive the blunt end of a phonograph

needle, the pointed end of the needle forming a penetrating point for the dart.

In testimony whereof I affix my signature in presence of two witnesses.

KARL HAMPTEL.
